TIN BOX INTENDED TO BE VACUUMIZED, OR
LIKE CONTAINER

Alan Fraser Cowan, Shirley, England, assignor
to The Metal Box Company Limited, London,
England, a company of Great Britain

Application August 30, 1935, Serial No. 38,632
In Great Britain September 22, 1934

5 Claims. (Cl. 220—31)

This invention relates to tin boxes or like containers intended to be vacuumized and has for its object to provide an improved construction whereby uniformity of production obtains.

5 According to the present invention a box or like container intended to be vacuumized has a lid hinged thereto, and the box is provided with a curled or beaded edge and one hinge member on the box is formed in an extension of the 10 curl or bead and engages loosely the other hinge member on the lid, whereby a hinge is formed allowing play and the lid is free to seat itself on the curl or bead.

By making the hinge member of the box in an 15 extension of the curl an evenness is obtained by the curling operation which produces a perfect seating for the lid, hence if packing material is disposed between the curl and the lid a standard production suitable for vacuumizing is 20 always obtained, whilst if the lid is hinged with free play the hinge joint gives the lid full freedom to seat itself on the even curl so that an hermetically sealed box may be obtained under reduced pressure, and when the vacuum is destroyed the lid remains connected to the box.

The sealing medium may be an elastic band or a plastic mass. If a band is used the latter 25 may have a tab which projects and may be pulled to displace the band and break down the vacuum, or if a plastic mass is used the box or lid may have a pin hole closed by a removable patch or cover as well known in the art.

Experience has shown that if the curl does not extend wholly around the mouth and an attempt 30 is made to bend over metal between the ends of a curl to form one member of a joint that it is impossible to assure the evenness of seating required to assure standard production or the continuity required to assure a seal.

40 In order that the invention may be more clearly understood, reference will now be made to the accompanying drawing which shows by way of example preferred embodiments thereof.

In the drawing:—

45 Fig. 1 is a transverse sectional view of one form of construction according to the invention;

Fig. 2 is a perspective view of the container shown in Fig. 1;

50 Fig. 3 is a perspective view on an enlarged scale of the hinge construction shown in Figs. 1 and 2;

Figs. 4 and 5 are perspective views of modified forms of hinges;

55 Fig. 6 is a perspective view of a modified construction of container;

Fig. 7 is a perspective view of the container body shown in Figs. 1 and 2; and

Fig. 8 is a transverse sectional view of a further modified construction.

In the drawing like reference numerals designate the same or similar parts.

In one form of manufacture according to the invention the box is formed from a rectangular blank comprising a lateral extension from which the hinge member is to be formed.

10 The blank is then drawn and shaped to required form and the periphery curled or beaded so that a continuous and even curl (or bead) obtains at the mouth. The extension which, by the curling operation is pointing downwardly 15 from the bead, is then bent up.

The resultant container body is shown in Fig. 7 in which 1 is the body portion, 2 the curled or beaded edge and 3 the extension.

A lid 4 (Figs. 2 and 3) is provided with a skirt, 20 or flange or extension 5 formed to drop into the bent up extension 3 and is slotted at 6 to give entry through the skirt 5 of the free end of the extension 3, the slot being sufficiently large to permit vertical displacement of the lid at the hinge. The beaded edge of the cover flange thus forms a pintle adapted to be received within the extension 3 which forms a socket.

25 By such an arrangement the lid may be turned about the hinge and when over the box may fall 30 parallelly to the curl.

The lid 4 is formed to locate packing material over the bead and extension and to this end may be dished to form a wall about which a band 7 may be disposed (as shown in Fig. 8) or the 35 lid may be formed with a peripheral groove 8 to locate plastic material or a band 7 in the lid.

The wall of the container may be formed with a groove or with an indentation or bead as shown at 14 in Fig. 1 for supporting a coin or other implement by means of which the lid may be levered off without first breaking the vacuum.

40 Means may be provided, however, for destroying the vacuum before the lid is removed.

In the construction shown in Fig. 1 a pin-hole is provided in the bottom of the container and this hole is closed by a removable patch or closure as known in the art.

45 The edge of the lid opposite the hinged joint and/or the wall between the hinged joint and the 50 front of the lid may be provided with protuberances 9 to catch under the bead or curl 2 on the periphery of the box to retain the lid 4 closed when once the vacuum has been broken.

55 From the foregoing it will be observed that

many variations may be made in the hinge joint without departing from the invention. For example, the extension 3 from the bead may extend laterally from the box as shown in Fig. 4 and be slotted as at 10 to admit freely a tongue 11 depending from the lid 4, the tongue 11 being, for example, curled and/or upset as at 12 to prevent return through the slot.

The extension 3 on the box previously described with reference to Figs. 1, 2 and 3 may be formed with a rib or shoulders as shown at 13 in Fig. 5, to limit the angle of tilt of the lid in the "open" position.

Moreover, although the invention has been explained by reference to an embodiment in which one extension only is used, clearly instead of one hinge a box according to the invention may be provided with a plurality.

An example of a box having two such hinges is shown in Fig. 6.

The invention has been described in its particular application to a tin box but the invention applies also to other containers, whether made of metal, plastic material, such as that material known on the market under the registered trademark "Bakelite", or containers of glass, whether transparent or opaque and in such constructions a neck ring is secured to the body of the container so that a lid may be attached to the ring and co-operate therewith to form a closure in exactly the same way as if the ring was the wall of the body of a tin box.

In using the term "ring" reference, of course, is only made to the endless form of the member attached to the container and not to its specific shape, such member may be of hexagonal, oval, square or of other polygonal form.

Further, it should be understood that the invention applies also to tin boxes or containers in which the lid is made of a mouldable material or is cast whether or not the body portion is a tin box or a container of other material as previously referred to.

In referring to the edge of the mouth of the container as being provided with a curled edge, this term is intended to include not only rolling over the edge to obtain a full curl but a mere flanging or bending over to obtain what may be referred to as a part or open curl.

Although the invention has been described in its particular application to a box of rectangular form, the invention is equally applicable to a box of circular or oval form provided the extensions in the lid and the box are relatively narrow so as to permit a turning movement about the curved periphery of the box and clearly also the box may have other curved or curvilinear shapes.

What I claim is:—

1. A box or like container adapted to be vacuumized comprising a body portion having an outwardly curled or beaded edge, a lid, a gasket secured to said lid and adapted to engage said bead for sealing the container, said curled edge on the body being extended downwardly, thence outwardly, thence upwardly and inwardly, said lid having a skirt formed with a slot for receiving the inwardly extending portion of said extension whereby said lid is hingedly connected to said body portion, said slot being of sufficient width so as to enable the lid to seat freely upon the container before the container is vacuumized.

2. A box or like container adapted to be vacuumized comprising a body portion having an outwardly curled or beaded edge, a lid, a gasket secured to said lid and adapted to engage said bead for sealing the container, said curled edge on the body being extended downwardly, thence outwardly, thence upwardly and inwardly, said lid having a skirt formed with a slot for receiving the inwardly extending portion of said extension whereby said lid is hingedly connected to said body portion, said slot being of sufficient width so as to enable the lid to seat freely upon the container before the container is vacuumized, said upturned portion of the extension being provided with shoulders adapted to engage the lid and serve as stops to limit the tilting movement of said lid.

3. A box or like container adapted to be vacuumized, comprising a body portion having an outwardly curled edge, a lid, a gasket secured to said lid and adapted to engage said curled edge for sealing the container, said lid having a depending flange rolled at the lower end thereof to form a bead providing a hinge pintle, the curled edge of said body portion being extended downwardly to partially encircle and engage the hinge pintle formed by the bead on said lid, said hinge pintle occupying only a portion of the space within the extended curled edge of said body portion whereby to permit limited vertical movement of said lid relative to said body portion so as to enable the lid to seat freely upon the body portion before the container is vacuumized.

4. A box or like container adapted to be vacuumized, comprising a body portion having an outwardly curled edge, a lid, a gasket secured to said lid and adapted to engage said curled edge for sealing the container, said curled edge of the body portion having a depending extension bent outwardly, upwardly and inwardly to form a hinge member, said lid having a depending skirt and a depressed peripheral portion forming a recess for said gasket, said skirt having a bead at the lower edge thereof and a slot in the region of said hinge member on the body portion, said inwardly extending portion on the extension passing through said slot and being of a thickness less than the vertical width of said slot for loosely connecting the lid to the body portion whereby to enable the lid to seat freely on the body portion before the container is vacuumized.

5. A box or like container adapted to be vacuumized, comprising a body portion having an outwardly curled edge, a lid having a depending flange provided with a beaded edge and having a peripheral bed adjacent said flange, a gasket disposed in said peripheral bed and adapted to seat against the curled edge of said body portion, and a hinge joint connecting said lid with said body portion and including a socket integral with the curled edge on said body portion and a pintle formed by a portion of the beaded edge on the lid flange, said pintle extending within said socket and only partially occupying the space within said socket whereby to permit the lid to seat freely upon the container before it is vacuumized and also to permit the pintle to move downwardly a distance greater than the amount of reduction in thickness of the gasket when the container is vacuumized.

ALAN FRASER COWAN.
